UNITED STATES PATENT OFFICE.

ADOLPH LOWY, OF NEW YORK, N. Y.

DESIGN FOR A FASTENER MEMBER FOR SUITCASES.

45,814.

Specification for Design.

Patented May 19, 1914.

Application filed February 6, 1914. Serial No. 817,074. Term of patent 3½ years.

To all whom it may concern:

Be it known that I, ADOLPH LOWY, a citizen of the United States, residing in the city of New York, in the county and State of New York, have invented a new, original, and ornamental Design for a Fastener Member for Suitcases, of which the following is a specification, reference being had to the accompanying drawing, forming part thereof.

In the drawing, Figure 1 is a plan view.

of the device, and Fig. 2 is an end view, and Fig. 3, a side view of the device, embodying my new design.

What I claim is:—

The ornamental design for a fastener member for suitcases, as shown.

February 2d, 1914.

ADOLPH LOWY.
